(57) **CLAIM**

The ornamental design for an escutcheon, as shown and described.

DESCRIPTION

FIG. 1 is a left, top, front perspective view of an escutcheon showing my new design in use condition;

FIG. 2 is a front elevational view thereof;

FIG. 3 is a left side elevational view thereof, the right side elevational view thereof being a mirror image of the left side shown;

FIG. 4 is a top plan view thereof;

FIG. 5 is a bottom plan view thereof;

FIG. 6 is a rear elevational view thereof;

FIG. 7 is a sectional view taken along line 7—7 of FIG. 4;

FIG. 8 is a left, top, front perspective view of the escutcheon of FIG. 1 showing my new design in another use condition; and,

FIG. 9 is a right, top, front perspective view of the escutcheon of FIG. 1 showing my new design in another use condition. The broken line showing of a mirror in FIGS. 1-8 and of a cabinet with an opening for a plumbing fitting in FIG. 9 is included for the purpose of illustrating environmental structure only and forms no part of the claimed design.

In a preferred embodiment, the nature of this product is an escutcheon such as for the base of a mirror stand or covering an opening for a plumbing fitting.
